CENTRIFUGAL PUMP WITH SELF-PRIMING CHARACTERISTICS

Henry H. Kroeger, Montclair, N.J., assignor to Worth-
ington Corporation, Harrison, N.J., a corporation of
Delaware

Filed Oct. 23, 1958, Ser. No. 769,201

3 Claims. (Cl. 103—103)

This invention relates generally to the pumping of 10 fluids and more particularly to an improved centrifugal pump design for pumping a heterogeneous mixture of liquids, gases and solids.

It is well known that the pumping of heterogeneous mixtures of liquids, gases and/or solids presents a difficult pumping problem for a centrifugal pump because such mixtures adversely affect the performance characteristics of the pumps and cause unstable operation where the pumps are not designed to handle this type of fluid mixture. This is particularly so when the pump is designed primarily for handling homogeneous fluid.

When a pump designed for handling a substantially homogeneous fluid is required to pump a heterogeneous mixture of liquids, gases and solids it is believed that secondary movement of the fluid being pumped is progressively reduced to a minimum and finally the pump is rendered inoperative by gas binding.

It is believed that this occurs due to the counter-effect between the centripetal field and the discharge capacity and pressure head. When a heterogeneous mixture of liquids, gases and solids is fed to the rotating impeller of a pump normally designed to handle a substantially homogeneous fluid the centripetal field produced by the rotating impeller will first act like a centrifuge separating and stratifying the various components of the mixture in accordance with their densities and, secondly, will induce a secondary of counterflow of the less dense components, i.e., the gases and like density materials flow towards the suction inlet or area of lower pressure in the passages formed in or relative to the impeller. This stratification and counterflow reduces the thru flow discharge capacity and pressure head of the pump. As the discharge capacity and pressure head is reduced there results a corresponding increase in the centripetal field which in turn increases separation, stratification and counterflow. Now a further reduction in the discharge capacity and pressure head occurs and the process repeats itself until a heavy layer of stratified material is formed about a core of separated gases in the center of the centripetal field which core will continue to build up until the various forces and pressures acting in the impeller and the flow passages are equal, at which point effective pumping ceases.

The present invention seeks to overcome the problem by providing a centrifugal pump wherein a helical motion is imparted to the fluid as it enters the vane of the impeller with the provision of a tongue in the pressure developing passage means formed in the impeller which flow fluid from the suction inlet to the discharge outlet. This helical motion is amplified at the outer periphery of the impeller and in the volute and discharge chamber with the provision of regenerative tips on the outer edge of the pressure developing passage means and formation of the volute to return fluid to these tips with the least amount of shock. The helical motion resulting coacts with a curvilinear flow pattern provided by a suction tube formed at the pump inlet to substantially reduce the aforementioned difficulties.

Accordingly, it is an object of the present invention to provide a centrifugal pump having an optimum design configuration for imparting a spiral or helical motion to the forward motion of a heterogeneous mixture of liquids,

gases and solids being pumped whereby a pump for this type mixture with good performance characteristic is provided.

It is another object of the present invention to provide a centrifugal pump having an optimum design configuration including a regenerative acting impeller tip of a pre-determined configuration and apparent to one skilled in the art which will impart a spiral or helical motion to the forward motion of a heterogeneous mixture of liquids, gases and solids being pumped, and which is further adapted in the portion of the vane channels for the impeller adjacent the periphery of the impeller and in the volute to accelerate the centrifugal component of the helical motion to a maximum when the thru flow decreases to zero thus providing self-priming characteristics in addition to high performance and stable operation in this type of pump when heterogeneous fluid mixtures or mixtures having high gas content or which froth or evaporate easily are handled.

It is another object of the present invention to provide a centrifugal pump having an optimum design configuration for imparting a spiral or helical motion to the forward motion of a heterogeneous mixture of liquids, gases and solids being pumped so that a hydrodynamic backflow cut-off is provided for the less dense part of the fluid either at the entrance of the impeller or in the point of flow between the discharge of the vane channels in the impeller and the volute; the backflow cut-off effect increases as capacity decreases and is at a maximum when capacity drops to zero thus providing good self-priming features for this design.

Further objects and advantages of the invention will become evident from the following description with reference to the accompanying drawings in which:

FIGURE 1 is a side view of a centrifugal pump partly in vertical section showing the invention therein.

FIGURE 2 is a vertical section taken on line 2—2 of FIGURE 1.

FIGURE 3 is a section taken on line 3—3 of FIGURE 2 with the impeller removed.

FIGURE 4 shows another form of centrifugal pump, partly in vertical section, showing a modified form of the invention.

FIGURE 5 is a side view of a centrifugal pump partly in vertical section, showing another form of the invention.

FIGURE 6 is a side view of a centrifugal pump partly in vertical section, showing still another form of the present invention.

FIGURE 7 is a fragmentary view of the pressure developing passage means of the impeller showing the tongue means for creating the helical motion.

FIGURE 8 is a fragmentary view of an open impeller showing the tongue means for creating the helical motion.

FIGURE 9 is a perspective view on line 9—9 of FIGURE 8 showing the tongue contemplated by this invention.

Referring to the drawings, FIGURE 1 shows a centrifugal pump including a casing generally designed 1 having a suction inlet 2, a discharge outlet 3, and a volute 4 which communicates with the discharge outlet as shown in FIGURE 2 of the drawings.

A shaft 5 extends through the side of the casing remote from the suction inlet side into an impeller chamber as at 6 which shaft is rotated by any suitable type of prime mover, not shown, as is well known in the art. Disposed in the impeller chamber 6 is an impeller 7 which is fixedly mounted on the end of the shaft 6 as by a threaded element 8.

In the present invention there are a number of distinct configurations which coact to impart the desired helical motion to the forward motion of the fluid being pumped,

These may be enumerated as: (a) the tongue 50 formed in the pressure developing passage means 51 formed between opposite vanes of the impeller 7; (b) the regenerative tips 17 of predetermined configuration formed on the outward edge of the pressure developing passage means 51; and (c) the configuration of the volute 4 for passing fluid discharged from the impeller back into the tips 16 in a shockless fashion.

Curvilinear flow path

Affixed to the portion of the suction inlet adjacent the impeller chamber 6 is an annular ring-like element 10 referred to as a suction tube. The inner face of this element provides a smooth continuation of the suction inlet up to the suction eye 9 of the impeller, which face as at 11 reduces from the diameter of the suction inlet to the diameter of the suction eye of the impeller to provide an area of variable cross-section as is clearly shown in FIGURE 1 of the drawings.

When fluid travels from the suction inlet through this annular ring to the suction eye of the impeller a pre-entrance flow path having curvilinear motion without rotation is developed. This curvilinear motion in such channel of variable cross-section will counteract separation and movement of lighter components of the heterogeneous mixture of fluids, gases and solids being pumped towards the low pressure areas of the impeller.

This is believed to occur in curvilinear motion because initial forces acting in the fluid and centrifugal forces developed in turning the fluid tend to produce secondary cross flows which move or carry the lighter components of the mixtures away from the walls in a direction normal to the bending of the flow lines produced by the shape of the passage carrying the fluid mixture. This result is advantageously applied to the present invention to prevent accumulation of gases at spots critical to the operation and performance characteristics of this pump.

In addition manipulation of the flow in a curvilinear fashion as is provided for by suction tube 10 also provides a block for the lighter fluids caught in the eye of the helix created by the means mentioned hereinabove to arrest it from passing back into the low pressure areas of the suction eye 9.

Tongue means

As the flow enters the pressure developing passage means 51 of the impeller 7 a helical motion is imparted thereto by the provision of tongue means 50 which comprises an extension of the vane forming a side of the passage means 51. The tongue formed of a predetermined configuration to thereby create a low pressure area therewith at 52 and accordingly induce a helical motion to the fluid passing through the passage means 51.

While FIGURES 1 and 7 show the tongue 50 formed on an impeller of the closed type it is not intended to limit the construction to this configuration as the tongue may be applied to an impeller of the open type as is shown in FIGURE 8 of the drawings.

Regenerative means

In order to impart the helical motion to the forward motion of the fluid being pumped through the portion of the vanes adjacent the periphery of the impeller and in the volute in the casing, the peripheral portion of the impeller is shaped as shown in FIGURE 1.

Thus FIGURES 1 and 2 show that the impeller includes a back shroud 12 continuous with the hub 13; a front shroud 14 of a lesser diameter than the back shroud, and a plurality of circumferentially disposed radially extending curved vanes 15.

The vanes have their inner or entering end disposed just inwardly of the suction eye 9 and extend in a curved rearwardly bending path beyond the periphery of the shorter front shroud 14 to the periphery of the rear shroud 12. The tip 16 of each of the vanes is shown in FIG-

URES 1 and 2 as having a cutback as at 17 formed of a predetermined configuration and one that will provide the particular helical motion demanded by the system to which the pump is applied. This regenerative tip coats with the volute as hereinafter described.

Configuration of the volute

The volute 4 can take a number of configurations which adapt it to coat with the regenerative tip for the impeller 7. The preferred form for the volute being a construction that will provide for return flow to the regenerative tips in a substantially shockless fashion and by way of example FIGURE 1 indicates a means of adapting a conventional volute to the present invention.

In FIGURE 1 the normal curvature of the volute is cut back on its forward or front face as at 18 to provide a smooth continuous chamber substantially circular in cross section which is continuous from the periphery of the rear shroud to the periphery of the front shroud.

Thus a portion of the volute 4 extends below the outermost point of the vane tip 16 and will coat with the cut-back portions 17 of each of the vanes 15 to allow the fluid being rotated by the impeller and pumped into the volute to reenter the portion of the vane channels 19 inwardly of the vane tip 16 to induce or accelerate the centrifugal component of the forward fluid flow pattern into the desired helical motion for producing the advantageous results in the present construction.

The strength of the centrifugal component of the fluid flow pattern will increase with the number of accelerating vane tips available. Accordingly, FIGURE 2 shows the use of additional splitter vanes as at 20 which are placed in the portion of the impeller adjacent the periphery of the back shroud 12, these splitter vanes 20 having the same regenerative type tips as the main vanes 15 above described.

Operation

In operation, when the shaft is rotated by the prime mover, not shown, the impeller rotates therewith.

Fluid enters the suction inlet 2 and passes subject to the curvilinear effect of the inner face 12 of the annular ring 11 as above described into the suction eye 9 of the impeller wherein a helical motion is imparted thereto by the tongue means and thence into the volute 4 in a manner substantially well known in the art.

However, by reason of the regenerative type tips as shown at 17 and the configuration of the volute as at 18, the centrifugal component in the forward motion of the fluid turns a portion of the fluid into those portions of the vane channels adjacent the periphery of the back shroud, where it receives additional momentum in coaction with the vanes of the impeller. This in and out movement between the volute and the vane channels imparts the added helical motion and causes the forward motion of the fluid being pumped to take on an amplified spiral effect which moves the gases and lighter substances towards the center of this flow of fluid and carries them out of the volute 4 to the discharge outlet 3 for the pump. In order to insure the discharge of the mixture of fluids, gases and solids from the volute as completely as possible it is desirable to provide a tongue 21 which is disposed between the discharge outlet and as close as possible to the outer periphery of the impeller. This tongue is also extended a slight distance into the volute as is shown in FIGURE 2 of the drawings.

Where self-priming characteristics are desired the tongue will be slotted as at 22 adjacent the wall of the volute. Since the gases and lighter components are trapped by reason of the hydrodynamic back-flow cut-off effect of the helical flow pattern, it is believed that only the outer heavier layers of liquid return through this slot to assist in continuing the pumping action of the pump thereby imparting the desired self-priming characteristics to the pump.

Modified form of the invention

FIGURE 4 shows a modified form of the invention. It differs from the form of the invention shown in FIGURE 1 in that the center line of the discharge end of the vane channels are offset from the centerline of the volute. This is done to increase the effective strength of the helical motion induced into the normal fluid flow pattern through the volute.

Thus, except for the volute configuration, all the parts are the same as those described for the form of the invention shown in FIGURE 1 of the drawings and, accordingly, these parts have been given the same character numerals as the parts shown in FIGURE 1.

The volute now designated 4' is shown in cross-section as beginning at the periphery of the back shroud 12 and extending in a somewhat ovoid configuration to a point in the impeller chamber 6 inwardly of the periphery of the front shroud 14.

This permits a deeper cutout as at 25 to be established on the forward face of the volute 4' and moves the centerline of the volute of the centerline of the discharge end of the vanes 15 as indicated by the lines C and C' in FIGURE 4.

Operation of this form of the invention is the same as that above described for the form of the invention shown in FIGURE 1. However, due to the offset relationship of the centerlines of the discharge end of the vanes 15 and the volute, the inward and outward movement of the fluid flowing through the volute is accentuated, thus increasing the strength of the helical motion imparted to the forward motion of this fluid.

Another form of the invention

FIGURE 5 shows a further form of the invention in which an open type impeller 30 has its vanes 31 cut back as at 32 to provide the regenerative tips similar to those above described for the form of the invention shown in FIGURE 1.

The volute 33, however, in this form of the invention is somewhat modified as indicated in FIGURE 5 which shows that in cross section the volute extends from a point in the impeller chamber designated 34 just inwardly of the periphery of the back plate 35 of the impeller in a rectangular-shaped arc to a point where the cutouts 32 of the vanes 31 of the impeller begin.

This permits a portion of the helically moving fluid to pass behind the back plate 35 and return through a plurality of openings 36 to the passages formed between the vanes 31.

Another form of the invention

FIGURE 6 shows a still further form of the invention and includes an open impeller 40 having vanes 41 cut back as at 42 to provide the regenerative tip similar to the form of the invention shown in FIGURE 5.

The volute 43 in this form of the invention combines features shown in both FIGURE 4 and FIGURE 5 in that the centerline of the volute as at D' is offset from the centerline D of the discharge end of the vane passages, and further that the volute also extends into the impeller chamber behind and just inwardly of the periphery of the back plate 44 for the impeller.

The cutout portion 45 in the forward face of the volute in this form of the invention is larger for the same purpose as set forth for the form of the invention shown in FIGURE 4 of the drawings.

Both forms of the invention shown in FIGURES 5 and 6 do not have the curvilinear entrance pattern shown in the FIGURE 1 and FIGURE 4 forms of the invention. However, by reason of the cutout portions forming the regenerative tips on the vanes the desired helical motion is imparted to the forward motion of the fluid passing through the volute.

While the preferred form of pump embodies most all

of the features enumerated above it is not intended to so limit the invention as satisfactory swirl of the fluid may be obtained by cutting the volute out as at 59 in a pump having a standard impeller, e.g., one without the cutback means to accomplish the desired helical motion to the forward motion of the fluid passing through the volute.

Of course the helical motion results by providing a volute will cause portions of the fluid being pumped through the impeller into the volute to reenter the impeller.

It will be understood that the invention is not to be limited to the specific construction or arrangement of parts shown but that they may be widely modified within the invention defined by the claims.

15 *What is claimed is:*

1. In a centrifugal pump of the self-priming type comprising a volute casing including a discharge outlet, an impeller chamber in said volute casing and communicating with the discharge outlet, a center suction inlet of a predetermined dimension formed in the volute casing and communicating with the impeller chamber, a rotatable shaft mounted in the volute casing and disposed in the impeller chamber, an impeller including a front and back shroud and said back shroud of greater dimension than said front shroud connected to said rotatable shaft and disposed in the impeller chamber, said impeller including vanes forming passage means therebetween and said vanes cut back from said front shroud to a portion thereof having about the same dimension as the back shroud to define a plurality of regenerative tips, the front shroud of said impeller defining an eye of lesser dimension than the dimension of the suction inlet, a suction tube means disposed in said suction inlet having an outer diameter of substantially the dimension of the suction inlet and said suction tube having an inner surface converging in dimension to form an inner diameter of the dimension of the eye of said impeller to provide a curvilinear flow path to the fluid entering the suction inlet, tongue means comprising extension on each vane and extending into the passage means to reduce the inner dimension thereof whereby a helical motion is imparted to the fluid passing through said impeller, and said regenerative tips coact with the volute casing to impart a helical motion to the forward motion of the fluid passing through 25 said volute to the discharge outlet.

2. The pump claimed in claim 1 wherein the portion of said volute casing adjacent said regenerative tips is cut back to coact with said regenerative tips to amplify the helical motion imparted to the fluid.

3. The pump claimed in claim 2 wherein splitter vanes are disposed between each adjacent pair of vanes and said splitter vanes include regenerative means formed at the discharge end thereof.
